UNITED STATES PATENT OFFICE.

WESLEY A. SMITH, OF SIOUX CITY, IOWA.

FAUCET.

Application filed June 6, 1924. Serial No. 718,365.

To all whom it may concern:

Be it known that I, WESLEY A. SMITH, a citizen of the United States, residing at Sioux City, in the county of Woodbury and State of Iowa, have invented new and useful Improvements in Faucets, of which the following is a specification.

This invention relates to a faucet and more particularly to an automobile radiator filling faucet and has for its primary object the construction of a faucet which may be automatic in its operation.

An object of the invention is the construction of a faucet of automatic operation constructed of very few parts substantially connected.

Another feature of the invention relates to the provision of a construction in which there is established a removable valve seat member together with a removable spout member and an outwardly facing shoulder against which the removable valve seat member may be clamped by the spout itself when connected into place. This arrangement makes it possible to insert or remove the valve seat member through the spout opening and in extremely simple and direct manner and without the necessity of providing additional opening in the casing which would entail additional machining operations, cost of manufacture, and possibilities of leakage.

Another feature of the invention relates to the provision of a construction in which there is provided a flexible diaphragm or gasket through which extends the operating member by which the valve on the inside of the casing is compelled to move by force applied at the outside of the casing, said diaphragm or gasket lying substantially parallel to the liquid passage through which the liquid flows to the valve member itself, and said diaphragm or gasket lying between the position of the liquid inlet connection and the valve member. Such a construction is to be clearly distinguished from one in which the diaphragm or gasket is placed at the opposite side of the valve member with respect to the liquid inlet connection.

A feature of my invention is the novel manner of connecting the parts so that they may be readily disconnected and the casing readily cleaned.

With these and other objects in view the invention will be better understood from the following detailed description taken in

connection with the accompanying drawing wherein:

Fig. 1 is a side elevation of my improved faucet. 60

Fig. 2 is a longitudinal sectional view.

Fig. 3 is a sectional view of a modification.

Fig. 4 is a sectional view of another modification. 65

Again referring to the drawing illustrating one of the many constructions of my invention the numeral 1 designates a casing having an inlet 2 and an outlet 3 in which is mounted a spout 4. Arranged adjacent 70 the inner end of the spout is a valve seat 5 which may be formed directly above the spout as a removable seat such as the ring 6. My improved valve device 7 consists of a valve 8 for cooperation with the valve 75 seat ring 6 and to this valve 8 is attached a rod 9 extending lengthwise through the liquid passage of the casing and with its other end formed into a boss 10. The casing is provided with an opening 11 in which 80 is mounted a flexible ring 12 and a cap 13.

The boss 10 sealingly engages in an opening in the ring 12 and is attached to an operating lever 14 by the screw 15. It will be noted that this lever extends towards 85 the spout and is provided with a bearing 16 rockable in a sufficient recess 17 in the cap.

In Fig. 3 I have shown a ball 18 in place of the boss 10 so as to facilitate rocking action and in Fig. 4 I have illustrated an 90 angularly shaped rod 19 to take care of the bend 20 in the casing.

Preferably there is established a shoulder 6^a in the casing 1, which shoulder faces outwardly through the same opening into 95 which is threaded the upper end of the spout 4. The ring 6 is set up against said shoulder by introduction from the outside through the same opening into which the spout itself is threaded, and this ring is 100 locked into place by the further action of threading the spout into place. It is thus evident that all of the machining operations necessary to be performed in the casing around the position of the valve seat may be 105 performed through the spout opening itself. This will eliminate additional machining operations with corresponding reduction of manufacturing expenses and possibly of leakage.

Furthermore, the replacement or 110 adjustment of the ring may be readily effected from time to time by simply remov-

ing the spout which is a very simple operation.

From the foregoing description taken in connection with the accompanying drawing it will be apparent that in the insertion of the spout 4 into an opening to a tank or other form of receptacle the lever 14 will be struck by adjacent surfaces and tilting same and opening the valve for allowing 10 the liquid to pass through the casing and make its exit out of the spout.

It will be noted that the diaphragm or gasket 12 is placed at a position intermediate between the liquid inlet connection 2 and the 15 position of the valve member 8. Consequently, the liquid flowing through the valve member travels past this diaphragm or gasket. Furthermore, said diaphragm or gasket lies substantially parallel to the liquid 20 passage and parallel to the valve operating rod 9. As a consequence, the connection from the outside of the device to the valve operating rod is effected through the wall of the casing at a point intermediate between the liquid inlet and the position of 25 the valve member. Such an arrangement is to be clearly distinguished from one in which the operating connection is made at the other side of the valve member with 30 respect to the liquid inlet connection as, for example, in certain prior art constructions with which I am familiar.

It is, of course, to be understood that the connection between the valve and handle 35 may be accomplished in other ways than illustrated and the valve may be constructed in various other manners and mounted in other relations, therefore, I do not desire to be limited in any manner except as set forth in the claims hereunto appended.

Having thus described my invention what I claim is:

1. A device of the class described comprising in combination an elongated body member having a longitudinally extending liquid passage, there being a liquid inlet connection at one end of said passage and a spout opening reaching into the other end of said passage and substantially at right angles to the direction of the passage, an outwardly facing shoulder in said spout opening, a valve seat removably entered into said spout opening and against said shoulder, a spout removably entered into the 55 spout opening and clamping the valve seat against the shoulder, another opening in the wall of the body member at a position intermediate between the inlet connection and the spout, a flexible diaphragm in said opening 60 lying substantially parallel to the direction of the passage through the matter, a rock arm extending longitudinally through the liquid passage, means in conjunction with said arm extending through the diaphragm 65 in liquid tight fashion to the outside of the

device, means in conjunction therewith for rocking the arm, and a valve member on the free end of the arm movable towards and from the valve seat aforesaid, substantially as described.

2. A device of the class described comprising in combination a body member having a longitudinally extending liquid passage, an inlet connection at one end thereof, there being an opening in the member reaching into said passage substantially at right angles thereto, an outwardly facing shoulder in said opening, a valve seat removably located in said opening and against said shoulder, a removable spout located in said opening and against the valve seat and serving to clamp the valve seat against the shoulder, a valve member within the casing, and means operable from the exterior of the casing effectively to move said valve member away from the valve seat, substantially as described.

3. A device of the class described comprising in combination a body member having a longitudinally extending liquid passage, a liquid inlet connection at one end thereof, a liquid delivery opening communicating with the other end of said passage, an outwardly facing shoulder in said liquid delivery opening, a circular valve seat member located in said opening and against said shoulder and removable outwardly with respect to the device, a spout removably located in said opening and against the valve seat member and serving to clamp said member against the shoulder, together with a suitable valve member on the interior of the device operable in conjunction with said valve seat member and controllable from the outside of the device, substantially as described.

4. A device of the class described comprising in combination a body member having a longitudinally extending liquid passage, a liquid inlet connection at one end thereof, a liquid delivery opening at the other end thereof and at right angles to the direction of said passage, a flexible diaphragm member in the wall of the body member at a position intermediate between the inlet and delivery openings aforesaid, a swinging arm extending lengthwise of the liquid passage from a position adjacent to said diaphragm member to a position adjacent to the delivery opening, means in conjunction with said arm at the position of the diaphragm member extending through said diaphragm member for swinging the arm from the outside of the device, and a valve on the free end of the arm movable with respect to the delivery opening, substantially as described.

In testimony whereof I affix my signature.

WESLEY A. SMITH.
